ABRADING APPARATUS

Loren E. Thompson, Parkersburg, W. Va.

Application March 12, 1943, Serial No. 478,925

7 Claims. (Cl. 51—217)

This invention relates to grinding machines.

An object of this invention is to provide a machine of this type which includes a reciprocal carriage movable transversely to the axis of the abrader or grinding wheel, the carriage being reciprocated by an improved hydraulic operator.

Another object of this invention is to provide in a machine of this type, a hydraulic operator for shifting the carriage toward or from the abrader.

A further object of this invention is to provide in a machine of this type an improved longitudinal operator for the carriage which is so constructed as to take up a minimum of space so that the maximum longitudinal carriage movement may be obtained in a space equal to the total length of such maximum movement.

A further object of this invention is to provide in a machine of this type an improved carriage and work support, the latter including a laterally shiftable saddle base and means for pivotally adjusting the saddle base relative to the support whereby the work may be fixed to the work support and the latter shifted about a vertical axis to thereby permit grinding of angularly related faces on the work without shifting the work relative to the support.

A further object of this invention is to provide in a machine of this type, a supporting base, a saddle base slidable laterally of the supporting base, the slidable connections between the saddle base and the supporting base being of such construction that the saddle base may be angularly adjusted in a horizontal plane.

A further object of this invention is to provide in a machine of this type an improved supporting base, a saddle base slidably carried by the supporting base, a saddle rockably carried by the saddle base, and a common locking means for locking the supporting base, saddle base and saddle against movement one relative to the other, so that the operator of the machine will not inadvertently leave one of these members in an unlocked position.

A further object of this invention is to provide in a machine of this type an improved saddle base and saddle with means for rockably adjusting the saddle.

A further object of this invention is to provide in a machine of this type an automatically adjustable shield for the saddle so as to prevent any particles from entering between the saddle and the saddle base.

The invention consists of the novel construction, combination and arrangement of parts as

will be more specifically referred to and illustrated in the accompanying drawings, but it is to be understood that changes, variations and modifications may be resorted to which fall within the scope of the invention as claimed.

In the drawings:

Figure 1 is a detail front elevation of a grinding or abrading machine constructed according to an embodiment of this invention,

10 Figure 2 is a detail end elevation of the machine,

Figure 3 is a fragmentary sectional view taken on the line 3—3 of Figure 1,

15 Figure 4 is a fragmentary sectional view taken on the line 4—4 of Figure 1,

Figure 5 is a fragmentary front elevation of the saddle base and supporting means therefor,

Figure 6 is a fragmentary top plan partly in section of the saddle base,

20 Figure 7 is a fragmentary sectional view taken on the line 7—7 of Figure 5,

Figure 8 is a fragmentary sectional view taken on the line 8—8 of Figure 7,

25 Figure 9 is a fragmentary sectional view taken on the line 9—9 of Figure 4,

Figure 10 is a fragmentary sectional view taken on the line 10—10 of Figure 5,

Figure 11 is an end elevation of the saddle base removed from the support,

30 Figure 12 is a fragmentary sectional view taken on the line 12—12 of Figure 1,

Figure 13 is a fragmentary plan view showing the connection between the saddle base and the operator therefor, and

35 Figure 14 is a fragmentary sectional view taken on the line 14—14 of Figure 13.

Referring to the drawings, the numeral 15 designates generally a base structure including a base member 16 and an upstanding hollow standard 17 rising from the base member 16. A motor or power member 18 is mounted on the upper end of the standard 17 and has secured to the armature shaft 19 thereof a pair of abrader holders 20 and 21 within which abrading wheels 22 and 23, respectively, are secured.

The machine includes a pair of vertically adjustable knees or supporting members 24 and 25 which are correlated with the abrading members 22 and 23, respectively. The knee or supporting member 24 is slidably carried by the standard 17, being slidably in vertically disposed guides 26 carried by one side of the standard 17. The knee or support 25 is slidably carried by the opposite side of the standard 17, being slidably on guides 27 carried by the standard 17

opposite from the guides 26. The knee 24 has mounted on the upper side thereof a saddle base or carriage 28 and a saddle 29 is adjustably carried by the saddle base 28.

A longitudinally movable work support 30 is carried by the saddle 29, being movable in a direction parallel with the adjacent face of the abrading wheel or member 22. The knee 25 has slidably mounted on the upper side thereof a saddle base or laterally shiftable carriage 31 and a rockable saddle 32 is carried by the saddle base 31. The saddle 32 has mounted thereon a longitudinally movable work support 33 which is movable in a direction parallel with the adjacent face of the abrading member 23. The knee constructions 24 and 25 with the apparatus mounted on the upper side thereof are of identical construction, and the description of one of these members with the apparatus correlated therewith will apply equally as well to the other member.

The knees 24 and 25 are independently operable and in like manner the saddle bases, and the work supports 30 and 33 are independently operable. The knee or vertically shiftable support 24 has formed integral with the opposite ends thereof a pair of upstanding guides 34 and 35, the guide 34 being provided in the upper side thereof with an inverted truncated keyway 36. The guide 35 is provided in the upper side thereof with an inverted truncated keyway 37. The central portion of the knee or support 24 is formed with a guide member 38 which has the upper face 39 thereof disposed slightly below the horizontal plane of the upper sides 40 and 41 of the guide members 34 and 35, respectively.

The saddle base 28 in the center thereof is formed with an enlarged base portion 42 which is provided in the lower side thereof with arcuate T-shaped channels 43. A plate 44 is interposed between the lower side of the base member 42 and the upper side of the guide member 38 and is formed with depending guide members 45 on the opposite sides thereof which slidably engage the guide or key member 38. A plurality of headed bolts 46 are extended through the guide members 45 and have the heads 47 thereof engaging in the T-shaped slots 43. The base 42 is pivotally secured to the plate 44 by means of a central pivot pin 48 extending through the base member 42 and into the plate 44. The lower end of the pin 48 is adapted to rest on the upper side 39 of the guide or key member 38. The bolts 46 with the heads 47 provide a means whereby the saddle base 28 may be swung in a horizontal plane and then locked in its adjusted position with respect to the knee or support 24. The guide member 38 with the sliding independent portions 45 provide a means whereby the saddle base 28 may be laterally shifted toward or away from the abrading member 22.

The keyway 36 has slidably mounted therein a key or slide member 49 and a keyway or guide 37 has slidably mounted therein a key or slide member 50. The two key members or slides 49 and 50 are of like construction and are adjustably locked with respect to the saddle base 28. The locking means for the two keys or slide members 49 and 50 are of identical construction and are shown in greater detail in Figures 4 and 9. The key member 50 is formed with an opening 51 which is substantially elliptical in top plan with the long axis of the opening 51 extending lengthwise of the saddle 28. The key member 50 is also formed with a second substantially elliptical recess 52 which communicates with the lower end

of the recess 51 and the recess 52 opens through the lower side of the key or slide member 50.

The saddle member 29 is formed with a partially cylindrical bearing surface 53 and a portion of the bearing surface 53 is adapted to seat in a concave seat 54 which is formed in the upper side of the saddle base 28. The saddle 29 is also formed adjacent the opposite ends thereof and in the convex lower side with T-shaped slots or channels 55. A saddle locking or clamping bolt 56 is adapted to engage in the T-shaped slot 55 and the bolt 56 extends downwardly through the base 28 and into the key or slide member 50. A cylindrical nut member 57 is threaded onto the bolt 56, being rotatable in an opening 58 formed in the saddle base 28. The nut member 57 also extends into the elliptical opening 51 of the slide member 50, and the lower end of the cylindrical nut member 57 is formed with a head or annular flange 59 which is mounted in the elliptical opening or recess 52.

A worm gear 60 is fixedly mounted on the upper end of the nut member 57 being rotatably disposed in an opening 61 formed in the saddle base 28. A worm 62 is carried by a worm shaft 63 which is journaled in the saddle base 28 extending inwardly from the forward side thereof and disposed on a downward inclination with respect to the horizontal. The worm 62 is adapted to mesh with the worm gear 60 so that rotation of the shaft 63 by means of a handle 64 which is secured to the outer end thereof will tighten or loosen the nut 57 and tighten or loosen the bolt 56. Rotation of the nut 57 will also have the effect of tightening or loosening the key member 50 with respect to the saddle base 28 so that when the saddle base 28 is swung about the pivot member 48, the elliptical openings 51 and 52 will provide compensating means to permit the horizontal swinging of the saddle base 28 without a corresponding swinging of the key members 49 and 50.

The saddle member 29 is provided with a pair of inner T-shaped slots 65 and T-shaped bolts 66 engage in the slots 65 and extend downwardly through openings 67 formed in the saddle base 28. Manually adjustable nuts 68 are threaded on the lower ends of the bolts 66 and these nuts are positioned between the upwardly projecting guide members 34 and 35 and the slide members 45. In order to provide a means whereby the saddle 29 may be rocked on the saddle seat 54, I have provided at a point between the ends of the saddle 29 worm gear teeth 69. A worm 70 is adapted to mesh with the worm gear teeth 69 and is mounted on a shaft 71 extending inwardly from the forward side of the saddle base 28. The outer end of the shaft 71 has secured thereto a handle 72 so that the shaft 71 may be rotated to adjust the saddle 29.

In order to provide a means whereby the material removed by the abrading member 22 will be prevented from working into the seat 54, I have provided on the front and rear sides of the saddle 29 a pair of flexible shields or guards 73 and 74 respectively. The shield 73 is secured by fastening means 75 to the saddle 29 adjacent the junction between the saddle 29 and the lower side of the work support 30. The shield or guard 73 is mounted on a spring roller 76 which is carried by the forward side of the saddle base 28 and the roller 76 is adapted to maintain the extended portion of the shield or guard 73 in a taut condition. The guard or shield 74 is secured by fastening means 77 to the upper portion of the

saddle 29 and the guard or shield 74 is wound on a spring roller 78 carried by the upper rear portion of the saddle base 28.

The head or guide 38 in the central portion thereof is provided with a horizontally disposed cylinder 79 which has heads 80 and 81 secured by fastening devices 82 and 83, respectively, to the front and rear ends thereof. A cylindrical sleeve 84 is rotatably mounted in the cylinder 79 and at its forward end abuts against a thrust anti-friction bearing 85. The rear end of the sleeve 84 abuts against a rear anti-friction bearing 86. A piston 87 is slideable in the sleeve 84 and the sleeve 84 is formed with a longitudinally extending spiral slot or passage 88. The passage 88 at its forward end communicates with an annular channel 89 which is formed in the outer side of the sleeve 84 and the rear end of the slot or passage 88 communicates with an annular passage 90 formed in the outer side of the sleeve 84 adjacent the rear end thereof. The cylinder 79 adjacent the forward end is provided with a fluid port 91 with which a fluid conducting pipe 92 communicates.

The cylinder 79 is also provided adjacent the rear end thereof with a fluid port 93 communicating with the passage 90 and a pipe 94 communicates with the port or duct 93. The two fluid conducting pipes 92 and 94 are connected to a common valve 95 which is connected to a fluid pressure pipe line 96 so that fluid under pressure may be selectively discharged into a selected end of the sleeve 84, in order to move the piston 87 in a selected direction. A return pipe 97 is also connected with the valve 95 so that when the fluid under pressure is flowing to one end of the sleeve 84, the fluid in the other end of the sleeve 84 may return through the pipe 97 and the valve 95 to the source of fluid pressure supply (not shown). The valve 95 may be manually operated, and if desired, suitable controls may be connected with the valve 95 for adjusting this valve from the adjacent front side of the knee or supporting member 24. It is also contemplated that the valve 95 be automatically adjusted so as to provide for the automatic advancement of the saddle base 28 toward the abrading wheel or member 22 after each passage of the work support 30 across the face of the wheel 22.

The piston 87 has secured thereto an upwardly extending connecting member 98 which has a portion 99 thereof projecting through the slot or passage 88. The connecting member 98 slidably engages in a longitudinally disposed straight slot or passage 100 which is formed in the upper side of the cylinder 79. An upwardly extending lug 101 extends from the connecting member 98 and a pin 102 extends through the lug 101. The pin 102 is disposed in a recess 103 which is formed in the base 44 and the pin 103 is locked against endwise movement by means of a plate 104 formed with an end flange 105 abutting against one end of the pin 102. The plate 104 is countersunk in a recess 106 formed in the upper side of the base member 44 and is secured in the recess 106 by fastening members 107. The recess 103 is of such a length that the pin 102 may be moved endwise in one direction a sufficient distance to permit removal of the pin 102 from the lug 101.

The saddle 29 is formed in the upper side thereof with a keyway or guide passage 108 within which a depending key or slide 109 carried by the work support 30 is adapted to slidably engage. The saddle 29 at a point below the key-

way or guide passage 108 is formed with a cylindrical opening 110 within which a cylindrical sleeve 111 rotatably engages. The sleeve 111 is similar in every detail to the sleeve 84 being provided with a longitudinally extending spiral slot 112 through which extends a connecting link 113 which connects a piston 114 slideable in the sleeve 111 with the slide member or key 109. The link 113 is secured within the key or slide 109 by means of a pin 115 which is formed with a reduced threaded stud 116 threaded into the key 109 as shown in Figure 12.

The saddle 29 is provided near the upper portion thereof with an opening 117 and the key or slide member 109 is provided with an opening 118 which is adapted to register with the opening 117 so that the pin 115 may be extended through the aligned openings 117 and 118 and threaded in operative position within the key member 109. The provision of the connecting link or member 98 between the saddle base 28 and the piston 87 provides for the elimination of the usual connecting rod which in most instances extends axially of the hydraulic piston and therefore provides an improved means whereby the maximum movement may be obtained for the saddle base 28 in a given space. This given space may be equal to the maximum movement of the saddle base 28 in either direction toward or away from the abrading wheel or member 22.

The improved connecting link and operator for the saddle base 28 also provides for the complete enclosing of the operating means for the saddle base so that no material removed from the work will contact with any of the operating parts of the saddle base operator. The provision of the self-contained operator for the work support 30 also provides means whereby the maximum movement lengthwise of the saddle 29 may be obtained for the work support 30, and the operating means for the work support will be entirely enclosed so that the removed abrasive or material will not interfere with the proper reciprocation of the work support under the movement of the work support operating piston 114.

In the use and operation of this machine, the motor 18 is connected to a source of electric current supply for rotating the abrasive members 22 and 23. The work is mounted on the upper side of the work support 30 and the entire carriage, which includes the saddle base 28, the saddle 29 and the work support 30, may be moved toward the wheel 22 by adjusting the valve 95 in order to effect inward movement of the piston 87. Where the work is to be ground with only a single flat face, the work may have such face disposed in parallel relation with the outer face of the abrasive wheel 22. However, if the work is to be formed with one or more angular faces, the saddle base 28 may be angularly adjusted with respect to the supporting member 24. This adjustment is obtained by loosening the bolts 66 and then loosening the nuts 57 which will release the slide or key members 49 and 50. The bolts 46 may then be loosened and the saddle base 28 swung about the axis of the pin 48. This angular adjustment in a horizontal plane may be within a predetermined limitation depending only on the long axes of the elliptical openings 51 and 52 in the key members 49 and 50.

When the saddle base 28 has been angularly adjusted to the desired degree, the handles secured to the two shafts 63 may be turned to lock the bolts 56, locking thereof tightening the

saddle 29 on the saddle seat 54 and also locking the key member 50 to the saddle base 28. Where a right angular adjustment is desired to dispose the upper side of the work support 30 on an angle to the horizontal, the saddle 29 may be rockably adjusted by rotating the handles 64 to shift the locked nuts 57 to a released position. The bolts 67 may also be loosened whereupon the saddle adjusting shaft 71 may be rotated in the desired direction to rock the saddle 29 in the saddle seat 54. Rocking of the saddle 29 in either direction will cause one of the guards or shields to be wound upon its correlated winding drum and the other of the shields will be pulled or unwound from its correlated winding drum.

When the saddle 29 has been angularly adjusted to the desired degree the lock nuts 57 may be turned by rotation of the shaft 63 and the worm 62 to cause tightening of the bolt 56 and the nut 57. When the two nuts 57 disposed adjacent the opposite ends of the saddle base 28 are locked tight with respect to the saddle base 28, this latter member may be moved toward or away from the abrading wheel 22 in its angularly adjusted position, and in the circumferential position of the saddle 29 with respect to the concave saddle seat 54.

It will be apparent from the foregoing that the work may be adjusted angularly with respect to the working face of the abrading wheel 22 in right angularly disposed planes, and may be shifted toward or away from the work in a plane parallel with the axis of the abrading member 22. By providing for the movement of the saddle base and the work support under the action of hydraulic operators which are independently actuated, it is possible to provide for a greater precision in the grinding or abrading operation than is possible where screw threads or gears are used for actuating these elements. It is of course well known that threaded shafts and gears gradually wear down and such wearing thereof prevents any precision work being performed by the abrading wheel 22. However, through the provision of the hydraulic operators, the wear on the operating parts of the operators is substantially eliminated so that it is possible to obtain precision abrading or grinding to a very close degree.

What I claim is:

1. In an abrading machine, a support, a saddle base on said support, means slidably mounting said base on said support, said means including an outer pair of parallel slide members disposed at substantially right angles to said base, means pivotally securing said slide members to said base, an inner slide member, means pivotally connecting said inner slide member to said base whereby said base may be horizontally swung about a vertical axis, and means locking said base relative to said outer slide members.

2. In an abrading machine, a support, a saddle base on said support, means slidably mounting said base on said support, said means including a pair of outer parallel slide members and an inner slide member, means pivotally connecting said slide members to said base, said base having at least one arcuate T-shaped slot concentric to said pivot means, and a headed bolt engaging said slot and extending through said inner slide member and means adjustably securing said outer slide members to said base.

3. In an abrading machine, in combination, a

support, a saddle base on said support, means slidably mounting said base on said support, said slide means including an outer pair of parallel slide members and means for angularly adjusting said base relative to said support and to said slide members in a horizontal plane, a saddle rockably carried by said base, a longitudinally movable work support carried by said saddle, and means angularly adjusting said saddle and work support relative to said base.

4. In an abrading machine, a saddle base formed with an elongated transversely concave saddle seat, a saddle having a convex seat engaging surface and formed with transversely extending T-shaped slots in the convex surface thereof, locking bolts engaging in said slots and said base, worm gear teeth formed in the convex surface of said saddle, a worm meshing with said worm gear teeth, a worm shaft rotatably carried by said base, an operator fixed to said shaft, a reciprocal work support carried by said saddle, and hydraulic means entirely within said saddle for reciprocating said work support.

5. In an abrading machine, a support, a saddle base on said support, means slidably mounting said base on said support, said means including a pair of outer slide members, and an inner slide member, means pivotally connecting said inner slide member to said base whereby said base may be swung about a vertical axis, a saddle rockably carried by said base, locking bolts for said saddle, said outer slide members having horizontally elongated openings therethrough, flanged nuts threaded onto said bolts and extending through said openings, worm gears fixed to said nuts, worms meshing with said gears, and worm operating shafts carried by said base.

6. In an abrading machine, in combination, an elongated horizontal support, an elongated saddle base seated on said support, said base having a longitudinal concave saddle seat in the upper side thereof, an elongated saddle formed with a convex lower side rockably engaging said seat, means mounting said base on said support for transverse sliding movement, said means including a central pivot about which said base may rotate, a pair of parallel slides for said base, a pair of guides for said slides carried by said support, said saddle having a pair of T-shaped channels in the lower side thereof, a headed bolt for each channel having the head thereof engaging in said channel, a nut rotatably carried by each slide and threaded onto said bolt, and means for rotating said nut whereby to simultaneously lock a slide relative to said base and also lock said saddle relative to said base.

7. In an abrading machine, in combination, a support, a saddle base on said support, means slidably mounting said base on said support, said means including an outer pair of parallel slide members, parallel guides for said slide members carried by said support, means pivotally mounting said base on said support for adjustment about a vertical axis, and releasable locking means for locking said slides to said base, said locking means including a threaded bolt, a nut threaded on said bolt and rotatably carried by a slide, gear teeth carried by said nut, and a threaded shaft engaging said gear teeth and adapted to rotatably adjust said nut to either slide locking or slide releasing position.

LOREN E. THOMPSON.
